Primary Examiner—Stella Reid

Assistant Examiner—Jean E. McCormick

(74) Attorney, Agent, or Firm—Lerner, David, Littenberg,
Krumholz & Mentlik, LLP(57) CLAIM

I claim the ornamental design for a furniture handle, as shown and described.

DESCRIPTION

FIG. 1 is a top plan view of a furniture handle showing my new design;

FIG. 2 is a right side elevational view thereof;

FIG. 3 is a left side elevational view thereof;

FIG. 4 is a rear, elevational view thereof;

FIG. 5 is a front, elevational view thereof; and,

FIG. 6 is a bottom plan view thereof.

The broken line showing in the views is for illustrative purposes only and forms no part of the claimed design.
